UNITED STATES PATENT OFFICE.

MORTIMER NORDEN, OF NEW YORK, N. Y., ASSIGNOR OF ONE-FOURTH TO JOSEPH NORDEN AND ONE-HALF TO SAMUEL ROTHAPFEL, BOTH OF NEW YORK, N. Y.

DESIGN FOR AN ELECTRIC SIGN.

49,491.

Specification for Design.

Patented Aug. 8, 1916.

Application filed June 16, 1916. Serial No. 104,116. Term of patent 7 years.

To all whom it may concern:

Be it known that I, MORTIMER NORDEN, a citizen of the United States, residing at the borough of Manhattan, in the city, county, and State of New York, have invented a new, original, and ornamental Design for an Electric Sign, of which the following is a specification, reference being

had to the accompanying drawing, forming part thereof.

The figure is an elevation of an electric sign, showing my new design.

I claim:

The ornamental design for an electric sign, as shown.

MORTIMER NORDEN.
